CARL D. BROWN, OF HOPEDALE, MASSACHUSETTS, ASSIGNOR TO DRAPER CORPORATION, OF HOPEDALE, MASSACHUSETTS, A CORPORATION OF MAINE

LOOM CONTROL

Application filed June 10, 1932. Serial No. 616,538.

The present invention relates to looms, and more particularly to the arrangement thereon of the controls for starting and stopping the same.

- 5 It is the usual practice to arrange looms, in a mill, in parallel rows, the looms in each row being positioned side by side as closely as may be without interference and all of the looms in a row facing in the same direction. 10 The looms in adjacent rows face in opposite directions, and space is left between the rows to constitute an alley-way. The alley toward which the front, or cloth take-up, ends of the looms face is known as the front 15 alley, and the next alley over, which is flanked by the back, or warp let-off, ends of the looms, is known as the back alley. Cross alleys are provided at varying intervals.

In accordance with accepted practice, the 20 weavers spend most of their time in the back alleys, from which position it is more convenient to tie in broken warp ends and detect and repair other faults in the warp sheet which might cause imperfect operation of 25 the looms. The duties of the weavers include the restarting of the looms after the repairing of defects in the warp or filling or after the loom has stopped from any other cause not requiring the attention of a loom fixer.

30 Obviously, if a loom fixer is stooped over fixing any of the various devices on the front or sides of the loom the restarting of the loom might injure him quite severely. Were the shipper handle to be placed at the back 35 of the loom there would be considerable danger of such injuries occurring, because, when a weaver discovers a loom stopped with no apparent defect in the warp or filling, the first act performed is to pull the shipper 40 handle to "on" position to determine whether the loom will run or not.

Accordingly, for the foregoing reasons, and for the convenience of the loom fixer in testing the loom after he has repaired it, it 45 has been considered necessary to place the shipper handle on the front of the loom. As a result, it has been necessary for the weaver in restarting the loom, either to reach entirely across the loom if that were physical- 50 ly practicable, or to walk a considerable dis-

tance in finding a cross alley by which to gain access to the front alley, where the shipper handle is more accessible.

It is, accordingly the principal object of my invention to provide a loom having an 55 arrangement of controls thereon which shall be more convenient for the weaver but which shall provide ample protection for the loom fixer against injury sustained from unauthorized or accidental starting of the loom. 60

More specifically stated, it is the object of my invention to provide, in a loom having a driving shaft, and a releasable clutch for applying power thereto, a shipper handle at the back of the loom for the weaver, a shipper 65 handle at the front of the loom, and means controllable from the front of the loom for rendering the shipper handle at the back of the loom inoperative.

Further objects of my invention will, in 70 part, be hereinafter more specifically enumerated and will, in part, become obvious as the description proceeds.

Referring to the accompanying drawings, which illustrate the preferred embodiment 75 of my invention:

Fig. 1 is a more or less diagrammatic plan view showing the relative positioning of a number of looms as they are usually arranged in the mills;

Fig. 2 is an elevation taken from the right hand side of one of the looms shown in Fig. 1, certain parts being omitted for sake of clearness;

Fig. 3 is a perspective view of a portion of 85 one of the shipper handles and contiguous parts; and

Figs. 4 and 5 are detail views of one of the parts appearing in Fig. 3.

As is more clearly shown in Fig. 1, looms 90 A, B, and C are placed side by side in a row, with their lays L almost touching and with their fronts, as evidence by the breast beam 1, all facing in the same direction. The looms D, E and F are similarly arranged except 95 that they face in the opposite direction to the looms A, B and C. The two rows of looms are, as shown, spaced apart a sufficient distance to form an alley way. Since this alley is the one that is flanked by the warp 100

let-offs W, which are always at the back of looms, it is known as the back alley. The front and cross alleys need not be herein illustrated.

5 Each individual loom is comprised, as is usual, of loom sides 2 connected by the breast beam 1 and suitable cross girths to form a frame which carries a driving shaft 3 for driving the lay L, the warp let off W, the 10 replenishing mechanism R, cloth take up T at the front of the loom (see Fig. 2) and other usual component parts which need not be herein illustrated or described. The means for supplying power to the driving 15 shaft may include a suitable electric motor 4 geared to a friction plate 5 constituting the driving element of a friction clutch 6. The elements of the clutch may be engaged and disengaged by any suitable arrangement of 20 levers operated by means of shipper handles positioned as hereinafter described.

As above indicated, prior to my invention is was customary to operate the clutch by one, or sometimes two shipper handles positioned 25 at the front of the loom. Such usual shipper handles, together with their connections to the clutch, have been employed in the present embodiment of my invention, as a matter of convenience. These shipper handles are 30 illustrated at 7 and 8 on the drawings.

The left hand shipper handle 7 is fixed to a shaft 9 journaled in bearings on the loom frame. The shaft 9 extends widthwise entirely across the front of the loom and the 35 shipper handle 8 is fixed to the right hand end of this shaft. A depending arm 10 is fixed to, and moves with, shaft 9, preferably by being formed integrally with shipper handle 8. A link 11 has one end bent to extend 40 loosely through an aperture in arm 10, being retained in the aperture by a cotter pin 12. Link 11 extends rearwardly adjacent the outside of the loom side and supports at its rearward end a head 13 to which are 45 pivoted levers 14 and 15 of a toggle. The outer end of lever 15 is pivoted to an arm 16 fixed to a block 17 which is, in turn, slidable axially of the clutch on a pin 18. Another arm 19, likewise fixed to the block 17, extends 50 rearwardly from the block to engage and operate the movable member of the clutch. It is apparent that when either of the shipper handles 7 or 8 is pushed rearwardly toward the loom the clutch is disengaged and when the handles are pulled forwardly the clutch is engaged.

As above intimated, I have added a third shipper handle 20 at the back of the loom for the convenience of the weaver. The shipper 60 handle 20 is pivoted to the loom frame at 21 and is connected to the head 13 on link 11 by means of a link 22. Links 22 and 11 are sufficiently resilient, to bend slightly, if necessary, to permit proper action of the toggle. 65 It will thus be seen that I have provided ship-

per handles at both the front and the back of the loom with connections from each of them for operating the clutch, or, from another point of view all of the shipper handles are rigidly connected together and to the 70 clutch whereby operation of any one of the handles will operate the other handles and the clutch.

In order to prevent the inadvertent starting of the looms from the back alley I have 75 provided means operable from the front of the loom for rendering the shipper handle at the back of the loom inoperative, the same consisting of a manually operable latch 23 carried by the front shipper handle 8.

The particular form of latch shown is comprised of a more or less triangular wedge pivoted on the bent end of link 11 where it passes through the aperture in arm 10 of the front shipper handle 8. The aperture 24 in the latch is of a size to fit loosely upon the link end, whereby the latch is pivotally suspended from the arm 10. The portion 10 of the shipper handle 8, to which the latch is pivoted, moves toward the loom frame to 85 engage the clutch and away from the loom frame to disengage the clutch. The latch member is of just the proper length, from aperture 24 to surface 25 of leg 26, to form a wedge extending between the loom frame 95 and the arm 10 of the shipper handle when the latter is in its position farthest remote from the loom frame, i. e. when the clutch is disengaged. The latch 23 may be manually rotated to this wedging position (see 100 dotted lines in Fig. 3) but is accessible only from the front of the loom. However, when it is so manipulated it effectively locks all of the shipper handles in off position.

Leg 27 of the latch 23 is slightly longer 105 than leg 26 thereof but has a surface 28 in the same plane as surface 25. Since the latter surface is normal to a line drawn radially of aperture 24 the surface 28 may be said to be eccentric of the aperture. Therefore 110 leg 26 and surface 25 form the wedge proper, which prevents movement of the arm 10 toward the loom frame, while leg 27 and surface 28 form a stop which prevents the latch from dropping down once it is rotated 115 (clockwise in Fig. 2 or counter clockwise in Fig. 3) to wedging position. The latch is, of course, released by manually rotating it counter clockwise, Fig. 2 or clockwise, Fig. 3.

Other means may be employed for carrying my invention into effect and it is, therefore, to be understood that detailed disclosure of the preferred embodiment is for purposes of illustration only and not of limitation, the true scope of the invention being defined in the appended claims.

I claim:

1. A loom including a frame carrying a warp let-off at the back and a cloth take-up 130

at the front thereof, a drive shaft carried by the said frame, means including a clutch for applying power to the said driving shaft, shipper handles disposed respectively at the 5 front and back of the loom, rigid connections between said shipper handles, and connections from one of the latter to the said clutch, and a manually operable latch carried by one of the shipper handles for carried by one of the shipper handles for en-
10 gagement with the loom frame to lock all of the shipper handles in off position.

2. A loom including a frame carrying a warp let-off at the back and a cloth take-up at the front thereof, a drive shaft carried by 15 the said frame, means including a clutch for applying power to the said driving shaft, shipper handles disposed respectively at the front and back of the loom, rigid connections between said shipper handles, and connec-
20 tions from one of the latter to the said clutch, and a manually operable latch carried by the front shipper handle and accessible only from the front of the loom for locking all of the shipper handles in off position.

25 3. A loom including a frame carrying a driving shaft, means including a clutch for applying power to the said driving shaft, a plurality of shipper handles carried by the loom frame, rigid connections between said 30 shipper handles, and connections from one of the latter to the said clutch, and a latch member pivotally suspended from one of said shipper handles and normally depending therefrom by gravity but manually movable
35 to extend from the shipper handle to the loom frame to thereby positively lock all of the shipper handles in off position.

4. A loom including a frame carrying a driving shaft, means including a clutch for 40 applying power to the said driving shaft, a shipper handle disposed at the front of the loom and connected to the said clutch, a portion of the shipper handle moving toward the loom frame to engage the clutch, and
45 moving away therefrom to disengage the latter, and a rigid latch member pivotally suspended from the said portion of the shipper handle, the latch member being of sufficient length to form a wedge extending be-
50 tween the loom frame and the said portion of the shipper handle when the latter is in position to hold the clutch disengaged.

CARL D. BROWN.
